UNITED STATES PATENT OFFICE.

GEORGE CALDER, OF SPOKANE, WASHINGTON, ASSIGNOR TO EDUCO COMPANY, OF SPOKANE, WASHINGTON.

BOOK-RACK.

1,285,932.

Specification of Letters Patent.

Patented Nov. 26, 1918.

Application filed February 12, 1918. Serial No. 216,781.

To all whom it may concern:

Be it known that I, GEORGE CALDER, a citizen of the United States, residing at Spokane, in the county of Spokane and State of Washington, have invented certain new and useful Improvements in Book-Racks, of which the following is a specification.

The present invention relates to improvements in book racks, designed especially for the purpose of supporting a single book in open position whether the book be of the end opening type such as a stenographer's note book, or of the side opening type such as a text book, novel or other literary production, and the primary object of the invention is the provision of a device of this character which is comparatively simple in construction and facile in its use, comparatively inexpensive of production, and well adapted and efficient in performing the functions for which it is intended.

The invention consists essentially in the combination and arrangements of wire frames which are specially made and which coöperate to provide a book rack for use on a desk, table, or other support, as will be hereinafter more fully described and claimed.

In the accompanying drawings one complete example of the physical embodiment of the invention is illustrated according to the best mode so far devised for the practical application of the principles of the invention.

Figure 1 is a front view of a device made according to the present invention.

Fig. 2 is a top plan view of the device, folded.

Fig. 3 is a side elevation or end view of the device in operative position.

Fig. 4 is a perspective view of the anchoring device, detached.

Fig. 5 is a detached plain view of the compensating leaf holder.

Fig. 6 is an end view or side elevation of the book rack supported in an elevated position by an elevating device forming part of the present article.

Fig. 7 is a top plan view of the elevating support, detached.

50 In the preferred form of the invention as illustrated in the drawings the book rack is made up of several frames shaped and fashioned in usual manner from wire stock, and the rack is of course made in suitable sizes for the accommodation of different sizes of

books. In making the rack a rectangular, or U-shaped frame is employed to form the front, book supporting member having a lower, central, straight bar 1 and the two end or side bars 2, 2, and these three bars 60 are connected by the upwardly curved rear supports 3 3 for the lower edges of an open book, and the angularly arranged bars or book rests 1^a 1^a which join the inner ends of the curved supports with the front center 65 bar 1. The bar 1 it will be noted is offset toward the front from the plane of the members 2 and 3, for the accommodation of the open leaves of a book supported on the rack.

At the ends 2' 2' of the wire forming this 70 front U-shaped frame, the frame is fixed, as by welding or brazing, to an inverted U-shaped frame whose upper portion comprises the two horizontal arms 4, 4, the top or intermediate arm 4' and the S bends 5 75 which join the arms 4, 4, to the central intermediate arm 4'. The two side bars 6, 6, of this inverted U-shape frame form posts for the front portion of the book rack and the caps or feet 7, preferably made of rubber, are attached at the lower ends of these posts, to prevent scratching or otherwise marring the desk or table top upon which the rack is to be used. The two posts 6, 6, are connected by a pair of cross arms or 80 bars 8, that are fashioned at their centers with backwardly curved or rounded parts 8' for the reception of the back edge of the book supported.

The upper portions of the leaves or pages 90 of a book, when resting in the rack, are supported and held back by means of the bail 9 having its looped ends 10 10 in frictional contact with the side bars 2, upon which bars the bail is adjustable. The bail is retained 95 in position, as in Figs. 1, 3, and 6, by gravity and its own weight, and may be adjusted as to altitude by sliding up or down on the posts or side bars 2. The looped ends are preferably located above the top of the 100 book and the body of the bail is thus suspended over the pages of the book with the looped ends 10 beyond the outer edges of the pages or leaves.

One of the especially meritorious features 105 of the invention is the leaf holder located at the lower end of the device and comprising a bracket 11 in the form of an ornamental plate 11 having turned ends 12 to form pivot sleeves on the bar 1, and at the upper 110

end of the bracket is fixed a tubular, curved, fixed arm 13 in which the similarly curved bar 14 is slidably supported. The utility of this compensating bar is enhanced and appreciated when the book is to be supported while open at the beginning or ending, as for instance when the reader has reached almost the end of the book, there are many pages at the left and that portion of the book is thick, while but few leaves remain at the right side of the book. In such an instance the compensating bar is slipped through the tubular casing to position shown in Fig. 5, and it will readily be seen that this slide bar may with facility be adapted for use in holding back the pages at both sides of the open book as the sides decrease or increase in thickness.

For the purpose of holding securely, the stenographer's note book, which opens at the end, the horizontal spring clip 15 is provided at the top of the rack, and at 16 is brazed to the intermediate arm 4' (see Fig. 2) so that the front portion of the open note book may be slipped into the spring clip with the remaining back portion of the book supported by the cross bars 8 8, and the bail 9 hanging over the pages. In this connection the bail may be used as a guide, if desired, for reading the lines of notes on the book, and may be slid down the side bars as the reading progresses, in usual manner.

There are two rear braces 17, for the rack, and these are hinged to the front frame by loops 18 on the S-bends 5, and the braces are anchored, to a table or desk, by the anchoring device 19, made up of wire, properly shaped and having its ends 20 embedded in a foot or rubber cushion 21, 21. A central, curved, slotted arm 22 is provided in the anchor for the set screw 23 by which the anchor is secured, in adjusted position, to the desk or table upon which the book rack is supported.

In use the book rack is positioned as in Figs. 3 and 6 with the front supporting frame and the rear braces, converging toward the top, and it will be readily apparent that the slant of the book supporting frame may be altered, by loosening the screw and swinging the rear braces on their hinges 18, to the front or rear, until the desired slant is attained, then the set screw is tightened and the rack is in proper position to support a book.

In some instances it is desirable that the rack be elevated, and for this purpose I

utilize an auxiliary device or elevator indicated as a whole by the number 24 (Fig. 7) and formed of two pivoted frames 25, 26, 60 with a screw or bolt 27 for the pivot and a wing 28 on the screw for clamping the frames in fixed relationship, as in Fig. 6, in operative position, and in Fig. 7 in folded or packed position. The front supporting frame has hooks 29 to support the front bar 30 through its eyes 30' of the elevator, and the anchor has a pair of parallel hooks 31 for the reception and retention of the loop 32. By means of the wing nut and screw, 70 the crossed frame of the elevator may be clamped in adjusted position in order to raise or lower the supported book, as desired, for the convenience of the reader. As indicated by dotted lines in Fig. 3, the book 75 or leaf retaining bracket, may be moved out of the way when the book is applied to the rack, the bail allowed to fall over the open pages, and as the leaves are turned, the compensating slide bar is moved as required. In this manner both end-opening and side-opening books may be accommodated in the rack, and when the note books, or end-opening books are being used, the spring clip at the top of the rack will of 85 course be used.

What I claim is:—

1. A rack including a rectangular frame for an open book and having a lower central horizontal bar, a bracket pivoted on the 90 bar, a curved, tubular casing having extended ends at the top of the bracket, and a similarly curved bar frictionally held in the casing and adjustable laterally to compensate for the difference in thickness of the 95 two parts of the open book, for retaining the pages.

2. A rack including a supporting frame for an open book, a bracket pivoted on the rack, a curved tubular casing on the bracket and a 100 similarly curved bar in the casing to engage the two parts of the book and slidably adjustable to compensate for their difference in thickness.

3. The combination with an open-book 105 supporting-frame and its side bars, of a horizontally disposed bail slidable on the bars, a pivoted bracket at the lower front of the frame, and a curved bar supported therein to engage the two parts of the book and slidably adjustable to compensate for their difference in thickness.

In testimony whereof I affix my signature.
GEORGE CALDER.
